FOLDING SUITCASE

Samuel L. Kleber, Pittsburgh, Pa., assignor to
Kleber Trunk & Bag Company, Pittsburgh, Pa.,
a corporation of Pennsylvania

Application April 10, 1943, Serial No. 482,531

2 Claims. (Cl. 190—41)

This invention relates to suitcases, and more particularly to the folding type which can be opened flat.

It is among the objects of this invention to provide a folding suitcase which is light in weight but strong and rigid, which opens flat, which can be hung up when open to permit garments to be hung in it full length, which protects the garments from dust when the case is open, which carries garments without wrinkling them, which has a shoe compartment inside, and which has luggage pockets on the outside of the case.

In accordance with this invention, my suitcase has a rigid rectangular top wall to the top of which a carrying handle is attached. A pair of side walls, preferably made from a non-rigid material such as fabric, are hinged at their tops to the opposite sides of the top wall. The end walls and bottom wall which are secured to the ends and bottom of the side walls are rigid so that the case has a rigid frame and is strong and durable. These end and bottom walls are divided lengthwise into half-sections to permit the case to be opened so that the side walls can be swung out into a common plane in which they are connected by the top wall. A ring or the like is attached to the outside of one of the bottom wall sections for hanging up the case after it has been opened. In the upper end of the open case there is a support for clothes hangers on which suits, coats, and other garments can be hung. As the garments can extend down into the lower half section of the case, they can be hung out full length or substantially so. To protect the garments when the case is open and to help hold them in place when the case is closed, a flexible curtain is hung from the upper end of the open case. When the case is closed, straps connected to the end portions of the top wall and extending across the outside of the curtain support the portion of the curtain adjacent the top wall. It will be seen that when the closed case is standing on its bottom the garments therein will extend from the hangers upwardly in one half of the case and over the straps and then downwardly in the other half of the case. The part of the curtain engaged by the straps is preferably stiffened transversely by a bar that is fastened across it to further aid in keeping the garments from wrinkling. The two sections of the case may be detachably locked together by suitcase latches mounted on the end walls of the case. A shoe compartment may be formed by a flexible partition in the lower end of the

open case. To provide space for clothing and other articles that do not need to be hung on hangers, and to make it unnecessary to crowd them into the interior of the suitcase, pockets are formed on the outside of the walls of the case.

The preferred embodiment of the invention is illustrated in the accompanying drawing in which Fig. 1 is a perspective view of my suitcase; Fig. 2 is a view of the open side of the case after it has been opened and hung up; Fig. 3 is a side view of the open case; and Fig. 4 is an enlarged vertical section through the folded or closed case.

Referring to Figs. 1 and 4 of the drawing, the closed suitcase is of the usual box-like shape defined by rectangular walls. The top wall 1 of the case is a rigid member which may be made from plywood. The ends of this wall turn down a short distance to form vertical flanges 2 which may be covered with leather to increase the wearing qualities of the case and to enhance its appearance. The rest of the top preferably is covered by a suitable long-wearing fabric, such as colored twill or duck. Attached to the central portion of the top is a leather handle 3 by which the case may be carried.

The case's end walls 5 and the bottom walls 6 (Fig. 4) joined thereto are made from a rigid material, such as fabric-covered plywood, which, with the top wall, form a rigid rectangular frame for the case. The upper end of the end walls extend up behind flanges 2 by which they are protected and prevented from bulging outwardly when the case is closed. The two side walls 7 of the case need not be rigid, and therefore to decrease the weight of the case they preferably are made from fabric stretched over sheets of stiffening material, such as cardboard. The ends and bottoms of the side walls are secured to the adjoining edges of the end and bottom walls. The upper edges of the side walls are hinged to the opposite sides of the top wall, preferably by stitching 8, as shown in Fig. 1. The tops of the end walls and the adjoining upper corners of the side walls may be reinforced with leather.

In order to permit the suitcase to be opened, the end and bottom walls are separated longitudinally substantially along their center lines into two half-sections. At the meeting edges of the wall sections one section is provided with an integral flange 10 (Figs. 2 and 3) that projects behind the edge of the adjoining section which is reduced in thickness at that point to receive it. The two wall sections thus interfit

as shown in Fig. 4 to make the case more rigid when it is closed.

The two half-sections of the closed case are locked together by the usual suitcase locks or latches 11 which are mounted on the lower portions of the end walls where they are readily accessible. To prevent any tendency of the bottom wall to warp or open up, a latch 12 is connected to its central portion, as shown in Figs. 2, 3, and 4. The bottom of the case is kept off the floor by hemispherical metal buttons 13 fastened to the corners of the bottom wall. These buttons or feet extend down into a plane below bottom latch 12 so that dirt will not get into the latch.

To open the suitcase it first is laid on its side or is turned bottom side up so as to rest on its top wall. The three latches are then easily opened, whereupon the two half-sections of the case can be swung outwardly away from each other to unfold and flatten out the case with the side and top walls all lying in substantially the same common plane. As shown in Figs. 2 and 3, the outside of one of the bottom wall sections carries a ring 15 by which the open case can be hung up on a hook or any other convenient support (not shown). This same wall section supports a U-shape bracket 16 inside the case for supporting hangers 17 on which garments 18 can be hung. Garments supported by these hangers may thus hang straight down into the lower half-section of the case in the same way as in a clothes closet, and therefore need not be removed from the case unless desired.

While the suitcase is open the garments are protected from dust by a flexible fabric curtain 19 suspended from the inside of the upper end of the case near its open side. The portion of the curtain hanging in front of the connecting top wall 1 supports a substantially rigid cross bar 21 of wood or heavy cardboard preferably mounted on the outside of the curtain. Attached to the inside of top wall 1 near its ends are two sets of straps 22 positioned to extend across the outside of the curtain above and below the cross bar. These straps are detachably and adjustably connected together by snaps 23 or the like. The purpose of the straps is to support the central portion of the curtain when the case is closed so that garments hung in the case behind the curtain will be supported by it adjacent the top of the case, as shown in Fig. 4. Otherwise, they would drop down into a pile in the lower part of the case and become wrinkled. The purpose of cross bar 21 is to prevent the curtain and straps from sagging toward the center of the straps which would permit the clothing therein to bunch up beneath the handle of the case instead of laying out flat. By having the cross bar on the outside of the curtain, its edges will engage the straps if it starts to move sideways, and thereby hold the curtain in place.

A thin or shallow pocket 25 is provided in the lower half-section of the open case by attaching the side and bottom edges of a rectangular piece of fabric to the back wall. The top of the pocket may be closed by a leather tab 26 provided with a snap fastener 27. Directly below this pocket there is a fabric partition 28 the upper edge of which is fastened to the back of the case. To provide a convenient way of detachably fastening the lower edge of the partition to the case without the use of metal fasteners, a rigid strip 29 of cardboard or wood is attached to the lower edge of the partition and is adapted to be insert-

ed between the lower end of the case and a thin rigid member 30 extending across the case directly above the lower end. The flexible partition bulges out and forms a shoe compartment in the case.

As there is little room for miscellaneous items of clothing and for toilet articles inside the case when several garments have been hung inside, and as any attempt to pack such things inside with those garments would tend to wrinkle the latter, provision is made for carrying clothing, papers, etc., outside of the case. Accordingly, a rather large pocket 32 is formed on the outside of each side wall of the case. Each of these pockets preferably is made of a fabric material and is of the bellows type so that it will lie flat against the case when empty but is capable of expanding considerably when necessary. Each pocket includes a flap 33 that folds down over its open top and carries straps 34 for connecting it to buckles 35 mounted on the outside of the pocket.

The folding suitcase disclosed herein is not only inexpensive, but also light in weight. For example, such a case twenty-one inches long, eighteen inches high, and six and a half inches across weighs only nine pounds. Yet, the case is strong and durable. It has an extra large capacity for its size, and carries garments neatly without letting them become wrinkled. Unless it is desired to use the clothing hanging inside, the case does not need to be opened on a trip because the apparel needed en route can be kept in the outside pockets.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A folding suitcase comprising a rigid rectangular top wall, a carrying handle attached to the top of said wall, a pair of side walls hinged at their tops to the opposite sides of the top wall, a pair of rigid end walls and a rigid bottom wall rigidly connected to the ends and bottom of the side walls, said end and bottom walls being divided longitudinally into half-sections whereby the side walls can be swung out into a common plane to open the case into two open half-sections connected by said top wall, means attached to the outside of one of said bottom wall sections for hanging up the open case, a clothes hanger support mounted in the upper end of the open case, a flexible curtain hanging from said upper end down into the lower half-section of the case, a substantially rigid bar fastened across the curtain in front of said connecting top wall, straps connected to the case adjacent the ends of said bar and extending across the curtain adjacent the opposite edges of said bar to support the curtain and to hold the bar against lateral movement after the case is closed, and means for detachably fastening together said two half-sections when the case is closed.

2. A folding suitcase comprising a rigid rectangular top wall, a carrying handle attached to the top of said wall, a pair of side walls hinged at their tops to the opposite sides of the top wall, a pair of rigid end walls and a rigid bottom wall rigidly connected to the ends and bottom of the side walls, said end and bottom walls be-

ing divided longitudinally into half-sections whereby the side walls can be swung out into a common plane to open the case into two open half-sections connected by said top wall, means attached to the outside of one of said bottom wall sections for hanging up the open case, a clothes hanger support mounted in the upper end of the open case, a flexible curtain hanging from said upper end down into the lower half-section of the case, a substantially rigid bar fastened across 10

the outside of the curtain in front of said connecting top wall, straps connected to the end portions of said top wall and extending across the outside of the curtain adjacent the opposite edges of said bar to support the curtain and to hold the bar against lateral movement after the case is closed, and means for detachably fastening together said two half-sections when the case is closed.

SAMUEL L. KLEBER.
